UNITED STATES PATENT OFFICE.

ANTHONY W. LOSHBOUGH, OF STURGIS, MICHIGAN, ASSIGNOR, BY MESNE ASSIGNMENTS,
TO STURGIS STEEL GO-CART COMPANY, OF STURGIS, MICHIGAN.

CHILD'S CARRIAGE.

No. 882,900.

Specification of Letters Patent. Patented March 24, 1908.

Application filed July 29, 1907. Serial No. 386,065.

To all whom it may concern:

Be it known that I, ANTHONY W. LOSHBOUGH, a citizen of the United States, residing at the village of Sturgis, county of St. Joseph, State of Michigan, have invented certain new and useful Improvements in Children's Carriages, of which the following is a specification.

This invention relates to improvements in children's carriages. It relates particularly to improvements in folding carriages such as are commonly designated as go-carts, although certain features are adapted for use in other relations.

15 The main object of this invention is to provide an improved folding carriage of the class described which is adapted to fold compactly and one in which the foot rest can be adjusted by means of the adjustable back.

20 Another object is to provide in a folding carriage an improved adjustable back.

Further objects, and objects relating to details of construction, will definitely appear from the detailed description.

25 I accomplish the objects of my invention by the devices and means described in the following specification.

The invention is clearly defined and pointed out in the claims.

30 A structure embodying the features of my invention is clearly illustrated in the accompanying drawings, forming a part of this specification, in which:

Figure 1 is a vertical section of my improved carriage taken on a line corresponding to line 1—1 of Fig. 3, looking in the direction of the little arrows at the ends of the section lines, one adjustment of the back being indicated by dotted lines; Fig. 2 is a 40 corresponding detail vertical section of the carriage folded or collapsed; and Fig. 3 is a detail rear elevation.

In the drawings, similar reference numerals refer to similar parts throughout the several 45 views.

Referring to the drawing, the side pieces 1 of the frame are relatively fixed or rigid and are provided with a handle at their upper ends. These side pieces are preferably curved 50 downwardly and forwardly at their lower ends, as clearly appears in Fig. 1, to carry the axles for the forward wheels. The side pieces 2 are pivotally connected to the side pieces 1 by the pivots 3. The side pieces 2 are made up of sections 4 and 6. The meet-

ing ends of the sections 4 and 6 are overlapped and secured together by the pivot 8, the ends of the meeting sections 4 and 6 being provided with laterally projecting arms 5 and 7 respectively, the pivot 8 being located between the arms. The spring 9 is connected to the arms 5 and 7 so that on the movement of the sections on their connecting pivots stress is put on the pivots, thereby providing a spring support for the rear axle. 60

A pair of side rails 10, having longitudinal slots 11 therein, are pivotally mounted on the fixed side pieces 1 by means of a suitable pivot rod as 13. The hooks 12 on the upper ends of the side pieces 2 are engaged in the slots 11 of the side rails 10, the hooks being adapted to slide back and forth in these slots as the carriage is collapsed or erected, the outer ends of the side rails swinging upward when the carriage is collapsed, as clearly 65 appears in Fig. 2.

A pair of side bars 14, which are adapted to serve as arms for the seat of the carriage, are pivoted to the side pieces 1 at 15, and are connected to the forward ends of the side rails by means of the links 16, the links being secured to the side bars by means of the pivots 17 and to the rails by means of the pivots 18. Mounted on these pivots 18 are a pair of arms 19 on which the foot rests 20 are mounted by means of the pivots 21. The supporting arms 19 are preferably connected by a brace bar 22. The seat 23 is carried by the rails 10, the back 24, the frame only of which is here illustrated, is pivotally mounted on the pivot rod 13 by which the side rails are connected to the side pieces as stated. The back 24 is provided with a pair of arms 25 which project downwardly and rearwardly from the pivots 13, and these arms are connected by the L-shaped links 26 to the supporting arms 19 for the foot rest, the links being connected to the lower end of the arms 25 by means of the pivots 27 and to the foot rest carrying arms by means of the 70

pivots 28. The back is adjustably supported by the bail-shaped support 29, the ends of which are mounted on the inner ends of the pivots 15, by which the side bars are connected to the side pieces 1 of the frame. 75 The support 29 is preferably formed of wire and provided with return bends 30 at its inner end, which are adapted to engage over the laterally projecting pins 31 on the back for securing the back in its inner position. 80

(See Fig. 1.) The support is also provided with the loop-like bends 32 which may be engaged on the pins 31 for supporting the back in a partially lowered position. The support 5 is further provided with shoulders 33 adjacent to its cross piece 34, which shoulders are adapted to engage the back for supporting it in its lowest position. This offset holds the cross arranged piece 34 of the support so that 10 the back does not engage therewith, affording a suitable handle for convenience in adjustment. I thus, by a very simple means, secure an effective adjustable support for the back. The outer ends of the pins 31 are supported by the straps 35 on the side pieces of 15 the back 24, which also serve as retainers for the side pieces of the back support.

The foot rest is preferably provided with rearwardly projecting fingers 36 adapted 20 when the structure is collapsed to engage the lugs 37 on the side rails, whereby the foot rest is folded or rocked up on its pivot.

I not only, by this arrangement, secure a collapsible carriage having a foot rest and 25 back adapted to be adjusted together, but one which folds very compactly, as will be obvious by a reference to Fig. 2 of the drawing.

Having thus described my invention, what 30 I claim as new and desire to secure by Letters Patent, is:

1. In a collapsible carriage, the combination 35 with the downwardly and forwardly projecting fixed side pieces, having a handle at their upper ends, of adjustable side pieces arranged across and pivoted to the said fixed side pieces; axles carried by said side pieces; side rails to which said adjustable side pieces are slidably connected pivotally 40 mounted on said fixed side pieces; side bars pivotally connected to said fixed side pieces; vertically-arranged links connected to the forward ends of said side rails and side bars; a foot rest; supporting arms therefor pivotally 45 mounted on connecting pivots for said links to said side rails; a seat carried by said side rails; a back pivotally mounted on the connecting pivots for said side rails to said fixed side pieces, said back having arms projecting rearwardly and downwardly beyond 50 the pivots thereof; L-shaped links pivotally connected to said arms on said back and to said foot rest carrying arms; pins on said back, and a bail-like support for said back pivotally mounted on the connecting pivots for said side bars to said fixed side pieces, said support having return bends adjacent to its pivots and loop-like bends in the side pieces thereof, said bends being adapted to 55 engage the said pins on said back, for adjustably supporting the same, said support also having shoulder-like offsets adjacent to the outer end or cross-piece thereof, for the purpose specified.

60 2. In a collapsible carriage, the combina-

tion with the downwardly and forwardly projecting fixed side pieces, having a handle at their upper ends, of adjustable side pieces arranged across and pivoted to said fixed side pieces; axles carried by said side pieces; side rails to which said adjustable side pieces are slidably connected pivotally mounted on said fixed side pieces; vertically arranged links connected to the forward ends of said side rails and side bars; a foot rest; supporting arms therefor pivotally mounted on the connecting pivots for said side rails to said fixed side pieces, said back having arms projecting rearwardly and downwardly beyond the pivots thereof; L-shaped links pivotally connected to said arms on said back and to said foot rest carrying arms; and means for adjustably supporting said back, for the purpose specified.

3. In a collapsible carriage, the combination 85 with the downwardly and forwardly projecting fixed side pieces, having a handle at their upper ends; of adjustable side pieces arranged across and pivoted to said fixed side pieces; axles carried by said side pieces; side rails to which said adjustable side pieces are slidably connected pivotally mounted on said fixed side pieces; side bars pivotally connected to said fixed side pieces; vertically arranged links pivotally connected to the forward ends of said side rails and side bars; a foot rest pivotally mounted on connecting pivots for said links to said side rails; a seat carried by said side rails; a back pivotally mounted on the connecting pivots for said side rails of said fixed side pieces, said back having arms projecting downwardly beyond the pivots thereof; links pivotally connected to said arms on said back and to said foot rest; pins on said back, and a bail-like support for said back pivotally mounted on the connecting pivots for said side bars to said fixed side pieces, said support having return bends adjacent to its pivots and loop-like bends in the side pieces thereof, said bends being adapted to engage the said pins on said back for adjustably supporting the same, said support also having shoulder-like offsets adjacent to the outer end or cross-piece thereof, for the purpose specified.

4. In a collapsible carriage, the combination 100 with the downwardly and forwardly projecting fixed side pieces, having a handle at their upper ends, of adjustable side pieces arranged across and pivoted to said fixed side pieces; axles carried by said side pieces; side rails to which said adjustable side pieces are slidably connected pivotally mounted on said fixed side pieces; vertically arranged links pivotally connected to the forward ends 105 of said side rails and side bars; a foot rest pivotally mounted on connecting pivots for said links to said side rails; a seat carried by said side rails; a back pivotally mounted on the connecting pivots for said side rails of

said fixed side pieces, said back having arms projecting downwardly beyond the pivots thereof; links pivotally connected to said arms on said back and to said foot rest, and 5 means for adjustably supporting said back, for the purpose specified.

5. In a collapsible carriage, the combination with the downwardly and forwardly projecting fixed side pieces, having a handle at 10 their upper ends, of adjustable side pieces arranged across and pivoted to said fixed side pieces; axles carried by said side pieces; side rails to which said adjustable side pieces are slidably connected pivotally mounted on said 15 fixed side pieces; a foot rest pivotally mounted on the forward ends of said side rails; a seat carried by said side rails; a back pivotally mounted on said fixed side pieces, said back having arms projecting rearwardly and 20 downwardly beyond the pivots thereof; L-shaped links pivotally connected to said arms on said back and to said foot rest carrying arms; pins on said back, and a bail-like support for said back pivotally mounted on the connecting pivots for said side bars to said fixed side 25 pieces, said support having return bends adjacent to its pivots and loop-like bends in the side pieces thereof, said bends being adapted to engage said pins on said back for adjustably supporting the same, said support also having shoulder-like offsets adjacent to the outer end of the cross-piece thereof, for the purpose specified.
6. In a collapsible carriage, the combination with the downwardly and forwardly projecting fixed side pieces, having a handle at 30 their upper ends, of adjustable side pieces arranged across and pivoted to said fixed side pieces; axles carried by said side pieces; side rails to which said adjustable side pieces are slidably connected pivotally mounted on said fixed side pieces; a foot rest pivotally mounted on the forward ends of said side rails, a seat carried 35 by said side rails; a back pivotally mounted on said fixed side pieces, said back having arms projecting rearwardly and downwardly beyond the pivots thereof; L-shaped links pivotally connected to said arms on said back and to said foot rest carrying arms; and 40 means for adjustably supporting said back, for the purpose specified.
- 45 7. In a collapsible carriage, the combina-

tion with the downwardly and forwardly projecting fixed side pieces, having a handle at their upper ends, of adjustable side pieces arranged across and pivoted to said fixed side 55 pieces; axles carried by said side pieces; side rails to which said adjustable side pieces are slidably connected pivotally mounted on said fixed side pieces; a foot rest pivotally mounted on the forward ends of said side rails; a seat carried by said side rails; a back pivotally mounted on said fixed side pieces, said back having arms projecting rearwardly and downwardly beyond the pivots thereof; links pivotally connected to said arms on said 60 back and to said foot rest carrying arms; pins on said back, and a bail-like support for said back pivotally mounted on the connecting pivots for said side bars to said fixed side pieces, said support having return bends adjacent to its pivots and loop-like bends in the side pieces thereof, said bends being adapted to engage said pins on said back for adjustably supporting the same, said support also having shoulder-like offsets adjacent to the outer end of the cross-piece thereof, for the purpose specified.

8. In a collapsible carriage, the combination with the downwardly and forwardly projecting fixed side pieces, having a handle at 80 their upper ends, of adjustable side pieces arranged across and pivoted to said fixed side pieces; axles carried by said side pieces; side rails to which said adjustable side pieces are slidably connected pivotally mounted on said fixed side pieces; a foot rest pivotally mounted on the forward ends of said side rails; a seat carried by said side rails; a back pivotally mounted on said fixed side pieces, said back having arms projecting rearwardly and downwardly beyond the pivots thereof; L-shaped links pivotally connected to said arms on said back and to said foot rest carrying arms; and means for adjustably supporting said back, for the purpose specified.

In witness whereof, I have hereunto set my hand and seal in the presence of two witnesses.
